DFS. 2040

Lindsay & Horner & John W. Bowvier
of New York, N.Y.

Letters Patent No. 2040 dated March 28, 1865

Design for the Standard of Bullion Scales

The schedule referred to in this Letters Patent and making part of the same.

To all whom it may concern:

Be it known that we, G. Horner
and John W. Bowvier of the City, County and State
of New York have invented a new Design for Bullion
Scales; and we do hereby declare that the following is a
full, clear and exact description thereof, which will enable
those skilled in the art to make and use the same, reference
being had to the accompanying drawing forming part of
this specification.

The drawing consisting of only one Figure
represents a pair of scales for use by Bankers, Banks and others
in weighing gold and silver, bullion and coin, constructed after our design.

The letter A, designates the scales.

The pedestal, A, rises from a platform B, whose front C is seen
in the drawing. To the front of the pedestal, C, is attached a
shield, D, from whose sides scroll E, E, extend as seen in the
drawing, a ball, F, is placed on the top of the pedestal, and on
the ball is placed an eagle with extended wings.

We claim as new and desire to secure by
Letters Patent the design above described, for ornamenting a platform
scales.
